UNITED STATES PATENT OFFICE.

FRANK D. CHAPMAN, OF BERLIN, WISCONSIN, ASSIGNOR TO BERLIN-CHAPMAN COMPANY, OF BERLIN, WISCONSIN, A CORPORATION OF WISCONSIN.

CONTINUOUS SHAKER.

Application filed October 27, 1923. Serial No. 671,187.

This invention relates to canning machinery, and particularly to a continuous shaker or agitating device for the cans of material.

The invention contemplates an arrangement including a container designed to be continuously rotated, whereby cans of material fed into the same at one end thereof will be caused to travel through the container and to be discharged at the other end. 10 The invention further contemplates the provision of means for periodically agitating or shaking the container, whereupon the contents of the cans may be agitated, and further for determining the period at which 15 said agitation commences and the length of the periods.

The invention further contemplates the provision of a structure wherein means are provided for balancing the shaker in such a manner that a single crank shaft may be efficiently employed for agitating one of the shaking containers, or whereupon a second container may be substituted for the balancing means, thus providing for the efficient 20 operation of the device under either of these conditions.

By an arrangement of this character it is possible to provide an efficient construction offering the possibility of a continuous 25 operating device wherein the container may be continuously rotated for causing the cans of material to be constantly fed therethrough, and during this rotation to provide means for periodically agitating the 30 container for periods of regulatable duration.

The details of construction of one illustrative embodiment of the invention, as well 35 as other novel features of construction, will be made more apparent as this description proceeds, especially when considered in connection with the accompanying drawings 40 wherein;

Figure 1 is a top plan view of a shaker constructed in accordance with this invention;

Fig. 2 is a side elevation thereof;

Fig. 3 is an end elevation on a somewhat larger scale;

Fig. 4 is a transverse sectional view, taken substantially on the plane indicated by the line 4-4 in Fig. 5;

Fig. 5 is a fragmentary longitudinal sec-

tional view of a portion of the container; and

Fig. 6 is a detail sectional view of drying means for the agitator shaft.

Referring now particularly to the drawings wherein like reference characters indicate like parts, it will be noted that there is illustrated a suitable base 10, upon which the device may be mounted, there extending, preferably longitudinally of this base, a skeleton drum 11, forming the outer portion of a container for the cans of material. 60 This container or drum 11 is reciprocably mounted upon horizontally arranged supporting members 12, the heads 13 of the drum being formed with sleeve-like extensions 14, slidably engaging the horizontal 65 supporting members 12 which in turn are rigidly supported in standards 15, extending up from and forming a part of the base 10.

Arranged within the frame 11 is a spiral 75 member 16, which co-operates with a rotary drum 17, provided with a plurality of longitudinally extending guides 18. The cans of material indicated at 19 in Fig. 4, are adapted to lodge between the guides 18 and the spiral guide member 16, so that upon rotation of the drum, the cans are fed longitudinally of the container 11. Associated with the container 11 is a can feeding means 19 and can discharging means 20.

Thus, during the rotation of the drum 11, the cans of material may be continuously fed into the frame, whereupon they will be caused to travel longitudinally thereof, as heretofore described, whereupon they will be also continuously discharged by means of the can discharge mechanism 20. The drum 17 is journaled, as at 21, in the heads 90 25 of the container 11.

Arranged transversely of the base is a crank shaft 22, this crank shaft being formed with three cranked portions 23, the center one of which is connected to the container 11 by means of a link 24. The other cranked portions 23 are connected by means of links 25 with a member 26, reciprocably mounted upon guide supports 27 in a manner similar to the container 11. The member 26 acts as a balance for the crank shaft 100 for balancing the container 11. Obviously, 105 if desired, this balancing reciprocable mem-

ber 26 may be removed and the connecting links 25 connected directly to another drum container 11. This arrangement therefore provides a construction for reciprocating one or two container drums with equal efficiency, in which the parts are at all times balanced, and lending itself to operation unimpaired by vibration.

As mentioned hereinbefore, the member 17 is mounted for rotation and for driving this member there is provided an internal gear 28, with which meshes a pinion 29, mounted upon a short shaft 30. This shaft has a slideable and splined connection with 10 the hub portion 31' of the level gear 31 and is driven thereby, and said beveled gear is in turn driven by a beveled pinion 32 fixed to a shaft 33. A belt wheel mounted on 15 the outer end of the shaft 33 has a belted connection 34 with a belt wheel 35 connected to a belt wheel 36 loosely journaled on the shaft 22. The hub portion 31' of the beveled gear 31 is journaled in the bearing 10' of the frame and its outer end is formed 20 with a head 31'' from which projects a wrist pin 37 and to which is connected a link 38. The opposite end of this link is pivotally connected to an arm 39, carrying a pawl 40, adapted to engage ratchet teeth 41 formed 25 on a wheel 42, to rotate said wheel step by step, as the shaft 30 is rotated. The said wheel 42 is mounted upon a stub shaft 43, which projects outwardly from the frame 15. The shaft 30 is provided with a collar 29' pinned thereto on the outer side of the head 13 to cause, in connection with the pinion 29 on the inner side of the head, the shaft 30 to reciprocate with the container 30 11 while being rotated by the splined connection with the beveled gear hub 31'.

The periphery of the wheel 42 is formed with a plurality of openings 44, circumferentially spaced to permit the attachment upon the inner side of the said disc of any 45 number of segmental members 45. These segmental members 45 are adapted to be mounted as desired, and determine the duration of the period of agitation imparted to the cans of food within the container 50 drum 11.

Journalled longitudinally of the drum 11, and at one side thereof, is a shaft 46, this shaft at the end opposite to the wheel 42 being connected to a belt shifter 47, which 55 carries a pair of arms 48 adapted to control a belt 49 and to shift the same from engagement with the pulley 36 to a joint engagement between this pulley and a pulley 50, keyed as at 51 to the shaft 22 (see 60 Fig. 6).

The front end of the shaft 46 carries an arm 52, which is adapted to engage the segmental members 45, fixed to the wheel 42, the arrangement being such that an engagement of the arm 52 with the segmental

member 45 will rotate the shaft 46 in such a manner as to shift the belt to drive the agitator shaft 22. Thus, if a sufficient number of the segmental members 45 are connected to the wheel 42, to fill one-half of the 70 circumference thereof, the drum will be agitated during one-half of the rotation of the wheel 42. In this manner, by varying the number of segmental members 45, the length of the period of agitation may be 75 consequently varied, thus providing automatic timing of the agitating period of the container drum 11.

A coiled spring 53, normally holds the belt shifter in the position shown in Figs. 1 80 and 3, that is in engagement with the wheel 36, mounted loosely upon the crank shaft 22, this spring consequently also maintaining the arm 52 in the path of the segmental member 45, so that during the rotation of 85 the wheel 42, the arm will be swung outwardly by these segmental members to agitate the belt shifter. Obviously, when the belt 49 rests entirely upon the drive pulley 33, the pulley 50 and consequently the 90 crank shaft 22, will not be rotated, but the drum 17 will be rotated for feeding the cans of material through the container drum 11.

Mounted upon the end of the crank shaft 22 is a brake wheel 54, a brake shoe 55 being pivoted to the frame adjacent the wheel, and adapted to be actuated by a link and lever arrangement 56, connected to the shaft 46. The arrangement of the parts is such that when the shaft 46 is rotated to shift 100 the belt 49 to the loose pulley 36, the brake shoe 55 will be swung into engagement with the brake wheel 54, to immediately stop rotation of the crank shaft 22, and consequently 105 the agitation of the container drum 11. 105

From the foregoing it will be immediately apparent that the cans of material may be constantly fed by gravity into the container drum 11, and inasmuch as the drum 17 contained therein is constantly rotated, 110 the cans of material will be fed through the container drum 11, and constantly discharged by the discharge mechanism 26.

By attaching to the wheel 42 the desired 115 number of segmental members 45, the length of the period of agitation of the container 11 may be varied so that at predetermined intervals, while the cans are being continuously fed through the device, the agitation of the contents of the cans may be accomplished. Obviously, the wheel 42 rotates at a comparatively slow speed, thus providing for an agitating period of considerable length, during each rotation of this 120 wheel 42.

It will be furthermore immediately apparent that the member 26, connected to the crank shaft 22, provides an efficient means for counter-balancing the drum 11 to eliminate disastrous vibration, the arrangement 125

offering the further possibility of removing the member 26 and connecting in its stead to the crank shaft 22, another drum, whereupon the capacity of the arrangement may 5 be doubled.

While one illustrative embodiment of the invention has been illustrated and described herein in some detail, it is not intended that the invention be unnecessarily limited, but 10 reservation is made to make such changes as may come within the purview of the accompanying claims.

Having thus described the invention, what is claimed is:—

15

Claims.

1. In a device of the class described, a rotating receptacle, means for periodically agitating said receptacle, and means for 20 varying the duration of the period of operation of such agitating means.

2. In a device of the class described, a rotating receptacle and means for periodically agitating said receptacle for predetermined 25 periods.

3. In a device of the class described, a continuously rotating receptacle, means for periodically agitating said receptacle, and means for varying the duration of the period 30 of operation of said agitating means.

4. In a device of the character described, a continuously rotating receptacle and means for periodically agitating said receptacle for predetermined periods.

5. In a device of the character described, a continuously rotating receptacle and means for periodically agitating said receptacle for variable periods.

6. In a device of the character described, 40 a continuously rotating receptacle and means for periodically agitating said receptacle for variable predetermined periods.

7. In a device of the character described, a can receiving receptacle, rotatable to continuously feed the cans therethrough, means for agitating said receptacle and means for automatically starting said agitating means.

8. In a device of the character described, a can receiving receptacle, rotatable to continuously feed the cans therethrough, means for agitating said receptacle and means for starting and for limiting the period of activity of said agitating means.

9. In a device of the character described, 55 a can receiving receptacle, rotatable to continuously feed the cans therethrough, means for agitating said receptacle and adjustable

means for starting said agitating means whereby said agitation will continue for predetermined periodic periods.

60

10. In a device of the class described, a rotating can receiving receptacle, an agitating means for said receptacle including a crank shaft and counter-balancing means for said crank shaft.

65

11. In a device of the class described, a rotating can receiving receptacle, an agitating means for said receptacle including a crank shaft, means connecting said receptacle to said crank shaft at one side thereof 70 and means connected to said crank shaft for balancing said receptacle.

12. In a shaker of the class described, a can receiving container provided with a constantly rotated part for continuously feeding cans therethrough, means for reciprocably mounting said container, means for reciprocating said container and a timer mechanism for periodically causing said reciprocating means to function.

75

13. In a shaker of the class described, a can receiving container provided with a constantly rotated part for continuously feeding cans therethrough, means for reciprocably mounting said container, means for reciprocating said container and a timer mechanism including a rotating member and removable segmental members for periodically causing said reciprocating means to function.

80

14. In a shaker of the class described, a can receiving container provided with a constantly rotated part for continuously feeding cans therethrough, means for reciprocably mounting said container, a power means for said container, a crank shaft connected to said container, and means for automatically coupling said crank shaft to said power means for reciprocating said container.

90

15. In a shaker of the class described, a can receiving container provided with a constantly rotated part for continuously feeding cans therethrough, means for reciprocably mounting said container, a power means for said container, a crank shaft connected to said container, means for automatically coupling said crank shaft to said power means for reciprocating said container and means for stopping said reciprocation when 105 said power means is uncoupled.

105

In testimony whereof, I affix my signature.

FRANK D. CHAPMAN.
